HAROLD C. ROOD, OF FAIRFIELD, CONNECTICUT

MAN'S GARTER

Application filed June 4, 1930. Serial No. 459,148.

This invention relates to hose supporters, and more particularly, to men's garters.

Heretofore, it was proposed to provide a pair of garters for supporting men's hose in which each garter of the pair was exactly the same and could be used optionally either for the right or left leg and yet have the fastening means on the detachable end of the leg-encircling band always located at 10 the inner side of the leg.

An object of this invention is to provide an improved garter of the general type above described which is more satisfactory in use, longer wearing and yet which may 15 be manufactured economically.

With these ends in view, the present invention consists of an improved garter for men's hose or socks having certain details of construction as will be hereinafter 20 described and pointed out in the appended claims.

In the accompanying drawings which illustrate one embodiment of this invention, that at present preferred—

25 Figure 1 is a perspective view of a garter made in accordance with this invention arranged to be worn on the right leg.

Fig. 2 is a front view of the garter shown in Fig. 1, but inverted so that it may be 30 worn on the left leg, the hose-engaging clasp having been rotated approximately 180° from the position in which it is located in Fig. 1 indicated in dot-and-dash lines to the position shown in Fig. 2.

35 Fig. 3 is a sectional view on an enlarged scale taken diametrically through the pad.

In the embodiment of my invention shown herein, the garter comprises a leg-encircling band 10 having an end 11 sewed to a pad 12

40 and having at its other end 13 a fastening loop 14 and intermediate its ends 11 and 13 a sliding buckle 15 for lengthening or shortening the band to fit the wearer's leg. This fastening loop 14 is adapted to be slid over

45 and catch onto a stud 16 having a head 17 and carried by the pad 12 to thereby fasten the end 13 of the band or web 10 to the leg of the wearer.

The garter has any usual or suitable form 50 of stocking gripping device 18 which may be

carried on a fabric band 19, which according to this invention passes through a slot 20 in a metal eye 21 carried by the stud 16.

One of the salient features of the present invention is the provision of improved means 55 for mounting the stud 16 on the pad 12 whereby none of the parts protrudes toward the leg of the wearer thereby avoiding the discomfort to the wearer and undue wear of the pad which results when the leg-engaging 60 surface of the pad is not substantially flat and smooth.

A further feature of this invention is the arrangement of the parts so that the metal eye 65 21 of the stocking gripping device will not rub upon and wear the fabric of the pad and whereby the fabric band 19 of the suspension member is kept from unduly rubbing against the parts of the pad so that the fabrics will not quickly become worn and frayed. 70

To this end, the pad 12 is made up of two layers 12a and 12b of fabric, the latter preferably having a soft surface 12c (such as is produced by the use of Canton flannel) to engage the leg of the wearer, and being applied 75 after the stud 16 has been assembled on the part 12a of the pad. The stud 16 is riveted to this pad and for this purpose has a reduced rear end of neck 22 which passes through a metal plate 23 at the outer surface of the layer 12a of the pad and through a washer 24 at the inner surface of the layer 12a of the pad. When the neck 22 of the stud is passed through the apertures in the metal plate 23 and washer 24 and through the layer 12a, a 80 shoulder 25 on the stud is brought into firm engagement with the outer surface of the plate 23 and then the end of the neck 22 is peened or spun over to form a rivet head 26. 85

If the plate 23 and the washer 24 were made substantially flat as heretofore, the head 26 of the stud would protrude beyond the rear surface of the layer 12a of the pad and would produce a hump on the layer 12b of the pad when the latter is put in place with the result that pressure would be brought to bear on one spot of the wearer's leg to his discomfort, and the slipping movement of the garter on the leg would soon cause the layer 12b of the pad to be worn through so that the metal 90 95 100

head 26 would ultimately directly engage the leg of the wearer.

To avoid this, it was previously proposed to sew a metal piece carrying the stud to the pad, but in such case the threads may break or be worn through by constant rubbing thereagainst by the outer garment of the wearer.

The difficulty has been avoided by the present invention by embossing the metal plate 23 so that it has a central raised portion 27 when viewed from the rear and forming a recess in which the layer 12a of the pad 12 along with the washer 24 may lie as shown in Fig. 3.

15 Likewise, the washer 24 has a recess 28 in which the spun-over head 26 of the stud 16 is completely located and hence does not protrude beyond the plane of the rear surface of the pad member 12a. By forcing the pad 20 into the depression in the rear face of the metal plate 23 by the washer 24, the plate is held firmly to the pad against rotation which, if permitted, would cause the fabric of the pad to be worn particularly by the edge of the 25 plate 23.

Of course in assembling the garter, the eye 21 is placed on the stud 16 before the neck 22 is inserted through the plate 23 and washer 24 before the stud is riveted over, and after 30 the parts are assembled on the layer 12a of the pad, the member 12b is secured thereto by rows of stitching 29 which, at the same time, may fasten the end 11 of the elastic web 10 to the pad if the end is inserted between the parts 12a and 12b before they are 35 sewed together.

The embossing of the metal plate 23 has a further advantage—namely, that of preventing the fabric band 19 from being worn by 40 rubbing against the pad, for, as indicated in Fig. 3, the slot 20 of the eye 21 is located beyond the raised portion 27 and thereby spaces the fabric band 19 from the adjacent metal plate 23 and pad 12.

45 The eye 21, according to the present invention, is loosely mounted on the stud 16 having its aperture 30 larger than the stud so that it can freely rotate from the position shown in dot-and-dash lines in Fig. 2 to that 50 shown in full lines, or oscillate in either one way or the other in either of these positions. Normally, the eye 21 is unconfined against lateral movement or floating movement on the stud 16 except by the plate 23 and the head 17 of the stud. In this way, it is so 55 freely mounted on the stud that, due to their weight, the fabric band 19 and stocking clasp 18 will fall perpendicularly from the garter, with the eye 21, of their own accord.

60 Yet, the eye 21 does not completely fill the space on the stud between the head 17 and the plate 23, for in addition to the eye 21, the stud is also adapted to be engaged by the fastening loop 14 which is slid between 65 the head 17 of the stud and the plate 23 when

the garter is fastened to the leg of the wearer. Even when the eye 21 and fastening loop 14 are located on the stud at the same time, the eye 21 has limited lateral movement and by pressing against the fastening loop 14 tends to hold the same on the stud against accidentally slipping off.

Variations and modifications may be made within the scope of this invention and portions of the improvements may be used without others.

Having thus described the invention, what is claimed as new and for which it is desired to obtain Letters-Patent, is:

1. A man's garter having a leg band; a fabric pad attached to one end of the leg band; a fastening loop attached to the other end of the leg band; a stud on the pad for engagement with the fastening loop; a metal eye rotatably mounted on the stud; a fabric band carried by the eye and supporting a stocking clasp; and a metal plate on the stud between the metal eye and the fabric pad, secured to the latter by the stud, and having a raised central portion adapted to be engaged by the metal eye to keep the latter from wearing the fabric pad and to space the fabric band from the pad to keep the band and pad from wearing each other.

2. A man's garter having a leg band; a fabric pad attached to one end of the leg band; a fastening loop attached to the other end of the leg band; a stud on the pad for engagement with the fastening loop; a metal eye rotatably mounted on the stud and carrying a stocking clasp; and a metal plate on the stud between the metal eye and the fabric pad to keep the former from wearing the fabric pad by its movement on the stud relative to the pad, said metal plate being secured to the pad by the stud.

3. A man's garter having a leg band; a fabric pad attached to one end of the leg band; a fastening loop attached to the other end of the leg band; a shouldered stud on the pad for engagement with the fastening loop; a metal plate on the stud located between the shoulder thereof and the pad and secured to the latter by the stud, said plate having a central concave portion; and a washer having a raised portion for forcing parts of the fabric of the pad into said concave portion when the raised portion of the washer is pressed into the central concave portion of the metal plate in making the garter.

4. A man's garter having a leg band; a fabric pad attached to one end of the leg band; a fastening loop attached to the other end of the leg band; a shouldered stud on the pad for engagement with the fastening loop; a metal plate on the stud located between the shoulder thereof and the pad and secured to the latter by the stud, said plate having a central concave portion; and a con-

5 cavo-convex washer having a convex portion fitting the central concave portion of the said plate for forcing part of the fabric of the pad into said concave portion of the plate when the end of the stud which protrudes through the washer is peened over to form a head in making the garter, said head lying within the concave portion of the washer.

10 5. In a man's garter, a pad having a stud projecting from one surface thereof, said pad being formed of two superposed parts; and means for riveting the stud to the pad comprising an outer plate and an inner washer embracing the outer one of the superposed 15 parts of the pad, said washer fitting within a recess in said plate and having a recess within which the riveted head of the stud lies completely, the other part of the pad covering the washer and riveted head of the stud.

20 20. Signed at Bridgeport, in the county of Fairfield and State of Connecticut, this 3rd day of June, 1930.
